UNITED STATES PATENT OFFICE

99,841

DESIGN FOR A DECORATIVE ELECTRIC LIGHT BULB OR SIMILAR ARTICLE

Abraham Abramson, New York, N. Y.

Application April 13, 1936, Serial No. 62,076

Term of patent 7 years

To all whom it may concern:

Be it known that Abraham Abramson, a citizen of the United States, and resident of New York city, in the Borough of Bronx and State of New York, has invented a new, original, and ornamental Design for a Decorative Electric Light Bulb or Similar Article, of which the following is a specification, reference being had to the accompanying drawing, forming part thereof, in

which Fig. 1 is a front elevational view showing my new design, and Fig. 2 is a side elevational view thereof.

I claim:

The ornamental design for a decorative electric light bulb or similar article, as shown.

Dated 11th day of April, 1936.

ABRAHAM ABRAMSON.
